UNITED STATES PATENT OFFICE.

GEORGE H. SAWIN, OF WORCESTER, MASSACHUSETTS.

COMBINED DOOR STOP AND LOCK.

SPECIFICATION forming part of Letters Patent No. 691,003, dated January 14, 1902.

Application filed April 28, 1900. Serial No. 14,700. (No model.)

To all whom it may concern:

Be it known that I, GEORGE H. SAWIN, of the city and county of Worcester and State of Massachusetts, have invented certain new and useful Improvements in a Combined Door Stop and Lock; and I do hereby declare that the following is a full, clear, and exact description thereof, reference being had to the accompanying drawings, forming a part of this specification, and in which—

Figure 1 represents a horizontal section through a door, its jambs, and a plan of my said improved door stop and lock, the same being combined with the floor and said door in holding the door open. Fig. 2 represents, upon an enlarged scale, a vertical section through part of the bottom of the door with the spring-latch of the locking device attached thereto, the same being swung up into a vertical position against its supporting-plate, fastened to the door, as when not in use. All the following figures are also upon the same enlarged scale. Fig. 3 represents a vertical section through part of the flooring, and a side view looking in the direction of arrow *a*, Fig. 4, of the door-stop and vertical holding-pin, over which the aforesaid spring-latch is fitted to hold the door, as will be hereinafter described. Fig. 4 is a horizontal section through part of the bottom of the door and showing a plan of my combined stop and lock device in the same position as in Fig. 1, and Fig. 5 represents a front detached view of the spring-latch of the locking device.

The object of my invention is to provide a device which shall serve as a stop or bumper for a door when opened and swung back, and whereby said door may be locked to the floor when thus opened and swung back; and it consists of a metal or other suitable plate adapted to be fastened to the floor and upon which are mounted an elastic stop or bumper and a vertical pin.

It also consists of a metal or other suitable plate adapted to be secured to the side of the bottom of a door and having pivoted thereto a spring-latch adapted to be engaged with the vertical pin on the aforesaid floor-plate, as will be hereinafter more fully set forth.

To enable others to better understand the nature and purpose of my said invention, I will now proceed to describe it more in detail.

In the drawings, *A* represents part of the floor, and *B* the door, to which are respectively secured the metal plates *CD*. The plate *C*, which is secured to the floor, has mounted thereon a suitable door stop or bumper *E* and also the vertical pin *F*. Said stop or bumper may be made in various ways. In this instance I have shown a cylindrical-shaped stud *E'*, projecting up vertically from the plate *C* and having a vertical groove *b* in the side next to the door, in which is fitted a piece of rubber *c* or other elastic material for the door to strike against when swung open, as is shown in Figs. 1 and 4 of the drawings.

The plate *D* on the door has formed thereon near its bottom edge two parallel vertically-arranged flanges or ears *D'D'*, between which fits the base end of the latch *G*, being pivoted thereto by the transverse pin *H*. Between said latch and the plate *D* is fitted a suitable spring *I* for exerting a pressure upon the base of said latch to hold the latch in any adjusted position. Said latch is also made of the proper shape to fit over and hold on the vertical pin *F*, projecting up from the floor-plate *C*. In this instance said result is accomplished by forming a hole *d* transversely through the plate constituting the outer end of the latch at the proper point to permit said pin *F* to pass up through it when the latch is sprung down over the pin, thereby detachably fastening the door to the floor-plate *C*, as is shown in Figs. 1 and 4. The latch is designed to be attached and detached to and from the pin on the floor-plate by means of the foot of the person opening and closing the door, and to facilitate said operation it is preferable to have a knob *e* formed on the outer end of said latch, under which the edge of the sole of the boot or shoe may be caught to raise the latch out of engagement with said floor holding-pin; but as it is not an essential feature I do not limit myself thereto, neither do I limit myself to the use of the spring *I* or to the exact construction shown of other parts of the device.

My device is intended mainly for large heavy doors in public buildings and is now so applied and its usefulness practically demonstrated. Its advantages are apparent without any detailed statement thereof. It may be readily applied to any door and is easily

operated in locking and unlocking the door, being operated by the foot without stooping to the floor, as previously stated.

Having now described my invention, what I claim therein as new, and desire to secure by Letters Patent, is—

1. A combined door stop and lock, comprising in combination the floor-plate provided with an elastic bumper and a holding pin or projection; the door-plate, a latch pivoted thereto, adapted to be engaged and disengaged to and from the aforesaid pin or projection, and a spring for exerting a pressure upon said latch, substantially as and for the purpose set forth.

15 2. The plate D, secured to door B and pro-

vided at its lower end with the parallel ears D' D'; latch G, provided with a transverse hole near its outer end and whose inner end is fitted between said ears D' D', and pivot-pin H, passed transversely through said ears and latch, in combination with plate C, secured to floor A and having the pin F projecting vertically therefrom; the elastic bumper c, and means for holding it in position on said plate C, substantially as and for the purpose set forth.

GEORGE H. SAWIN.
